UNITED STATES PATENT OFFICE

167,158

CABINET FOR BAKERY PRODUCTS
OR THE LIKE

John MacManus, Wellesley, Mass., assignor to Stop & Shop, Inc., Boston, Mass., a corporation of Massachusetts

Application May 4, 1951, Serial No. 15,065

Term of patent 7 years

(Cl. D80—11)

To all whom it may concern:

Be it known that I, John MacManus, a citizen of the United States, residing at Wellesley, in the county of Norfolk, and Commonwealth of Massachusetts, have invented a new, original, and ornamental Design for a Cabinet for Bakery Products or the like, of which the following is a specification, reference being had to the accompanying drawing, forming a part thereof, of which:

Fig. 1 is a view in perspective of a cabinet for bakery products or the like, showing my new design, with the doors thereof in closed position;

Fig. 2 is a view in perspective with the doors in opened position, and

Fig. 3 is a fragmentary view of a portion of the side wall thereof.

The dominant features of my design reside in the portions shown in full lines.

I claim:

The ornamental design for a cabinet for bakery products or the like, substantially as shown and described.

JOHN MACMANUS.
